UNITED STATES PATENT OFFICE

ROBERT MODELL, OF SACRAMENTO, CALIFORNIA

OIL-BURNING FIRE-BOX

Application filed December 7, 1928. Serial No. 324,516.

The invention relates to improvements in furnace fire-boxes and more particularly to those which are used in connection with boilers. Oil burners in connection with locomotives, crane engines, steam shovel engines, etc., not only produce excessive smoke under present conditions, but consume a great deal more fuel than is necessary, by permitting numerous unburned fuel units to escape, forming the smoke. Moreover, after the burners are turned off for a length of time and again lighted, the furnaces are prone to back-fire due to ignition of oil left upon the bottom of the fire-box incident to cutting the burners off.

The objects of my invention are to provide a new and improved construction for economizing in fuel and reducing the discharge of smoke, and to make provision whereby the bottom of the fire-box cannot be flooded with oil when the burners are turned off.

With the foregoing in view, the invention resides in the novel subject matter herein-after described and claimed, description being accomplished by reference to the accompanying drawings.

Fig. 1 is a longitudinal sectional view through the furnace of a locomotive boiler (preferably a passenger or switch engine) showing the novel construction of the fire-box bottom.

Fig. 2 is an elevation of the rear end of the fire-box bottom as indicated by line 2—2 of Fig. 1.

Fig. 3 is a vertical transverse sectional view through the fire-box bottom on line 3—3 of Fig. 1.

Figs. 4 and 5 are horizontal sectional views on lines 4—4 and 5—5 of Fig. 1.

Fig. 6 is another longitudinal sectional view showing the construction which is preferably followed in connection with the fire-boxes of freight, crane, steam shovel and analogous engines in which smoking is not so objectionable.

Figs. 7, 8 and 9 are sectional views on the correspondingly numbered lines of Fig. 6, the brick fire-box bottom being shown in end elevation in Fig. 7.

In the form of construction shown in Figs. 1 to 5 inclusive, F denotes the fire-box of a locomotive boiler B, T has reference to the fire-tubes at the rear end of the fire-box, and D designates the usual door at the front end of said fire-box. The fire-box bottom 10 is preferably flat and it is with the construction of this bottom and the arrangement of the fuel-supply means, that the present invention is concerned.

Formed longitudinally within the bottom 10 and extending substantially from back to front thereof, between its upper and lower sides, is a flame flue 11. Also formed longitudinally in the bottom 10 at opposite sides of the flue 11 and between the upper and lower sides of said bottom, are two flame-return flues 12, the three flues 11—12 being in communication at their front ends by a transverse flame-flue 13 which, like the other flues, is formed between the upper and lower sides of the refractory bottom 10. Two longitudinal slots 14 extend from the rear ends of the flues 12 through the upper side of the bottom 10.

The rear end of the flue 11 has its bottom downwardly offset, providing a vertical barrier 15, and the portion 16 of said flue bottom behind said barrier, declines rearwardly to an opening 17. A main burner 18 extends through the rear wall of the fire-box in position to direct fuel and flame forwardly in the flue 11, and under said main burner, a pilot-burner 19 also extends through said wall. This pilot-burner is positioned in opposed relation with the barrier 15 so that the flame projected forwardly from said pilot-burner will strike said barrier and not only maintain the latter at high temperature, but deflect upwardly, so that as soon as fuel is discharged from the front end of the main burner 18, it will be vaporized and ignited.

When lighting the pilot-burner, it is necessary to insert a quantity of fuel-saturated waste or the like into the opening 17 to initially heat said pilot-burner 19. The pilot-burner 19 will be kept burning as long as the boiler is in service. It is to be ignited one hour before the boiler is to be used.

The flame and any fuel units not yet ig-

nited, pass forwardly in the flue 11 and as the bottom 10 becomes highly heated, the unburned fuel units become more and more volatilized, so that by the time the flame has 5 traveled rearwardly through the flues 11 to the slots 14, all of said fuel is aflame and the flame is discharged into the fire-box F which is almost completely filled by said flame. It will thus be seen that a construction has been 10 provided which will effect economy in fuel, which will be highly efficient, and will be practically smokeless, due to the thorough combustion which takes place.

The construction so far described is prefer- 15 ably used in the boiler furnaces of passenger and switch engines, in connection with which the smoke from oil burners is now most ob- jectionable. However, use of this form of the invention is not restricted to any par- 20 ticular form of furnace.

Another advantage for the construction so far described, may be explained. When the burners 18-19 are turned off, any oil dis- 25 charging therefrom as the supply is finally cut off, cannot pass the barrier 15 and will drain down the bottom portion 16 of the flue 11, and discharge through the opening 17. Hence, there is no quantity of oil left in the flue to ignite and cause trouble when 30 an attempt is made to again light the burners.

The form of construction shown in Figs. 6, 7, 8 and 9 is preferably used in such fire- 35 boxes as those commonly employed on heavy freight engines, crane engines and steam shovel engines. In these views, the refrac- 40 tory fire-box bottom 20 is longitudinally channeled and the main and pilot-burners 18a-19a extend through the rear wall of the fire-box above the upper side of said bot- 45 tom. A barrier wall 15a however, is pro- vided across the rear central portion of the bottom 20 with its upper edge above the axis of the burner 19a, whereas said edge of the barrier wall 15a is below the axis of the 50 main burner 18a. Hence, while flame from the pilot-burner 19a will strike the barrier 15a, maintaining the latter at high tem- 55 perature and deflecting upwardly to ignite fuel from the burner 18a, the forward blast 60 of fuel and flame from this main burner 18a, will for the most part pass over said barrier. However, some flame from the main burner 18a will continually play upon the barrier 15a to maintain it at high temperature and 65 this is also true in connection with the burner 18 and the barrier 15 above described. Maintaining this highly heated part 15 or 15a immediately in advance of the main burner assists in initially gasifying the fuel 70 and insuring proper combustion.

Behind the barrier wall 15a, is an opening 17a, and a portion of the fire-box bottom 20 behind said barrier, declines to said opening. Hence, any oil dripping from the burners 75 80 when they are turned off, cannot pass the

barrier 15a but is drained out through the opening 17a. Consequently, the bottom 20 cannot be covered with a film of oil to ignite and cause a flare-back or back-fire when the furnace is again lighted. When initially 70 lighting, a quantity of fuel-saturated waste or the like is inserted into the opening 17a to initially heat the pilot-burner 19a.

The form of construction just described will be highly efficient and economical in 75 fuel consumption, but will produce a great deal more smoke than the construction first described. Hence, it is preferable that it be used only where smoke is not so objec- 80 tionable.

On account of the excellent advantages 85 existing from the details disclosed, they are preferably followed. However, within the scope of the invention as claimed, variations may be made.

I claim:—

1. A furnace fire box having a refractory bottom, a longitudinal flame flue extending from back to front of said bottom between the upper and lower sides thereof, return flame flues extending longitudinally of said bottom between its upper and lower sides, a transverse flame flue between the upper and lower sides of said bottom placing the front ends of the longitudinal flame flues in com- 90 munication with each other, and flame-escape openings from the rear ends of said flame return flues through the upper side of said bottom; together with a burner mounted at the rear end of the first named flue for 95 directing flame and fuel under pressure into the same.

2. A structure as specified in claim 1; the rear end of the bottom of the first named flue being provided with a downward offset to 100 provide a vertical barrier and being rear- wardly declined behind said barrier, and a pilot burner mounted to direct flame against said barrier, said fire-box bottom having an opening at the rear end of said declined por- 105 tion of said flue bottom.

In testimony whereof I have hereunto af- fixed my signature.

ROBERT MODELL.
